(57) **CLAIM**

The ornamental design for a charging station for mobile robotic vacuum, as shown and described.

DESCRIPTION

FIG. 1 is a front elevation view of a charging station for mobile robotic vacuum showing our new design, showing the prongs in a retracted position of use;

FIG. 2 is a top view thereof;

FIG. 3 is a bottom view thereof;

FIG. 4 is a right side elevation view thereof, the left side being a mirror image thereof;

FIG. 5 is a rear perspective view thereof;

FIG. 6 is a front perspective view thereof;

FIG. 7 is a front elevation thereof, showing the prongs in an extended position of use;

FIG. 8 is a top view thereof;

FIG. 9 is a bottom view thereof;

FIG. 10 is a right side elevation view thereof, the left side being a mirror image thereof;

FIG. 11 is a front perspective view thereof;

FIG. 12 is a rear perspective view thereof; and,

FIG. 13 is a front perspective view thereof, showing the prongs in a partially extended position of use.
